UNITED STATES PATENT OFFICE.

SAMPSON CISCO LAMP, OF DAWES, WEST VIRGINIA.

SCREW DRIVER.

Application filed May 18, 1923. Serial No. 639,960.

To all whom it may concern:

Be it known that I, SAMPSON C. LAMP, a citizen of the United States, residing at Dawes, in the county of Kanawha and State 5 of West Virginia, have invented new and useful Improvements in Screw Drivers, of which the following is a specification.

This invention relates to tools and has particular application to a screw driver, 10 the object being to provide a tool of this character including a movable section normally disposed centrally within the tool, but capable of being projected therefrom and held in position for use when desired, the 15 movable section converting the tool into a small screw driver when projected to a position for use, while a similar tool of larger dimensions is provided when the movable section is in normal position.

20 The nature and advantages of the invention will be better understood when the following detailed description is read in connection with the accompanying drawings, the invention residing in the construction, 25 combination and arrangement of parts as claimed.

In the drawings forming part of this application, like numerals of reference indicate similar parts in the several views, 30 and wherein:

Figure 1 is a view in elevation of the tool forming the subject matter of this invention.

Figure 2 is a longitudinal sectional view therethrough.

35 Figure 3 is a view of the tool with the movable section or small screw driver extended for use.

Figure 4 is a transverse sectional view taken on the line 4—4 of Figure 1.

40 Figure 5 is a similar view taken on the line 5—5 of Figure 3.

Figure 6 is a detail view of the movable section or small screw driver.

Referring to the drawings in detail, 45 indicates the handle of a screw driver, which together with the shank 11 is of hollow formation for a purpose to be hereinafter described. In addition to this fact, the handle 10 is provided at opposite sides with bayonet 50 slots 12. The working end of the tool is cut away as at 13 to receive the head or working end 14 of what I term a movable section, consequently a small screw driver as compared to the size of the tool proper 55 is provided. The shank 15 of this mov-

able section, or small screw driver slides centrally through the tool proper and is normally maintained within the latter by means of a spring 16. A connecting pin 17 is connected with the shank of the small 60 screw driver and this pin 17 projects through the bayonet slots above referred to.

As shown in Figure 2, the small screw driver is normally arranged with the head 65 or working end thereof positioned in the cutaway portion of the working end of the main shank, and consequently a screw driver of a large size is provided for. In this position of parts, the pin 17 is arranged in the 70 corresponding long branches of the bayonet slots. Now, when use of a small screw driver is desired it is only necessary to move the cross pin 17 longitudinally of the long branches of said slots, which projects the 75 small screw driver to a working position beyond the end of the shank 11, and by subsequently turning the pin 17 into the short branches of said slot, the small screw driver is held in working position against the tension of the spring secured to the same. The 80 small screw driver can be easily returned to normal position by turning the pin 17 in a reverse direction and arranging in the long branches of the slots.

While it is believed that from the foregoing description, the nature and advantages of the invention will be readily apparent, I desire to have it understood that I 85 do not limit myself to what is herein shown and described and that such changes may be resorted to when desired as fall within the scope of what is claimed.

Having thus described the invention, I 90 claim:

A screw driver having a hollow handle and a hollow shank providing the main screw driver, said hollow shank being notched at its working end, an auxiliary screw driver in said hollow shank and extending into said hollow head, oppositely disposed L-shaped slots in said head, a pin passing through said auxiliary screw driver within the head and having its end portions disposed in said L-shaped slots, a tension 100 spring within said hollow head, said tension spring normally holding the auxiliary screw driver in retracted position with its active end disposed in the notch at the active 105 end of the main screw driver and flush 110

therewith, and said auxiliary screw driver adapted to be moved into active position against the tension of said spring and dis-
pose said pin in the short arms of the L-
shaped slots to prevent casual turning move-
ment of the auxiliary screw driver relative
to the handle and to dispose the auxiliary

screw driver beyond the working end of the
main screw driver and at an angle relative
thereto.

10

In testimony whereof I affix my signature.

SAMPSON CISCO LAMP.
